CLAIM

The ornamental design for a card identification tab, as shown and described.

DESCRIPTION

FIG. 1 is a front perspective view of a card identification tab in a folded configuration, showing my new design.

FIG. 2 is a left-side elevation view thereof.

FIG. 3 is a right-side elevation view thereof.

FIG. 4 is a rear elevation view thereof.

FIG. 5 is a front elevation view thereof.

FIG. 6 is a top plan view thereof.

FIG. 7 is a bottom plan view thereof.

FIG. 8 is a top plan view of the card identification tab in an unfolded configuration.

FIG. 9 is a front perspective view of the card identification tab in use.

FIG. 10 is a left-side elevation view thereof.

FIG. 11 is a right-side elevation view thereof.

FIG. 12 is a rear elevation view thereof.

FIG. 13 is a front elevation view thereof.

FIG. 14 is a top plan view thereof.

FIG. 15 is a bottom plan view thereof; and,

FIG. 16 is a bottom perspective view of the card identification tab in an unfolded configuration.

The broken lines that illustrate the adhesive backing strips in FIGS. 1-4, 8, and 16 form no part of the claimed design. The broken lines showing a card in FIGS. 9-15 form no part of the claimed design.

1 Claim, 11 Drawing Sheets
